KARL R. PETERS, OF PHILADELPHIA, PENNSYLVANIA.

TOOL FOR TRUING UP CRANK SHAFTS.

1,406,756.

Specification of Letters Patent. Patented Feb. 14, 1922.

Application filed May 19, 1920. Serial No. 382,635.

To all whom it may concern:

Be it known that I, KARL R. PETERS, a citizen of the United States, and a resident of the city of Philadelphia, in the county of 5 Philadelphia, State of Pennsylvania, have invented a certain new and useful Tool for Truing Up Crank Shafts, of which the following is a specification, reference being had to the accompanying drawing.

10 My invention relates to a truing-up tool provided with a plurality of cutting elements arranged in circular order and adapted by suitable means to be simultaneously or "universally" moved radially during the 15 operation of the tool.

Among the objects of the invention is to provide a tool of the character above-mentioned for grinding or cutting bearings on a crank shaft particularly those used in automobile engines, without necessitating the removal of the shaft from the engine; which is adapted to be opened about a hinge or pivot to enable it to be inserted between the arms of the crank shaft respectively adjacent 25 the ends of the bearing to be operated on and then closed over the bearing for rotation thereon, which is so constructed that its several operating parts are held in proper relation at all times whether the tool is in 30 open or closed position and which comprises means adapted to feed the cutters of the tool "universally" or in unison for equal distances in radial directions while the tool is in operation.

35 My invention further contemplates the provision in a tool of the character aforesaid of a feed control element suitably divided to permit the component parts to separate when the tool is opened and to close together 40 when the tool is closed so as to form a continuous single operative element; further, the provision of cutting means arranged in diametrically opposed pairs effective to constantly and automatically maintain the tool 45 assembly in centered position on the bearing whereby the cutters perform both the function of cutting and of guiding the tool in its movement over the bearing surface, thereby avoiding the necessity of the use of additional guiding means such as has hitherto 50 been found essential in tools of this general character and the possibility of the tool being thrown out of alignment by the jamming of chips or burrs between such guiding element and the surface of the bearing. Moreover, my improved tool is so constructed as

to be thinner than the length of the bearing to be cut or ground, thereby enabling the tool assembly to be readily inserted and operated merely by disconnecting the connecting 60 rod and without the removal of the crank shaft from the main bearings of the engine.

Crank shaft bearings, particularly in internal combustion motors, become oval in cross-section from wear, and it has been the 65 practice heretofore, in "truing-up" worn bearings, to remove the crank shaft from the engine and place the same in a turning lathe or grinding machine to "true-up" the bearing to a circular form in cross-section. 70 Usually, the major axis of the oval exceeds the minor axis by about five or six thousandths of an inch. When the bearings are "trued-up" by the old methods, about forty to fifty thousandths of an inch of material 75 is removed or ground off, which greatly reduces the diameter of the bearing and usually requires the use of new bearing boxes. By my invention, however, only the excess metal along the major axis is removed, which amounts to about five or six thousandths of an inch of material, thereby obtaining a large saving of material usually lost by the old processes of bringing the 80 shaft to a uniform circular form. 85

Other objects of my invention will more fully appear from the following specification and upon the accompanying drawing.

Referring to the drawing:

Fig. 1 illustrates a top plan view of the 90 tool assembly with parts shown in broken section;

Fig. 2 is a view showing the manner of introducing and placing the tool about a bearing of a crank shaft in an automobile 95 engine;

Fig. 3 is a sectional view of a portion of the tool;

Fig. 4 is a detail fragmentary view of a portion of an automobile engine and a crank 100 shaft in place therein, showing the tool in place when in operation upon a bearing of the shaft; and

Fig. 5 is a detail end view showing the mode of keying certain elements against rotation but permitting longitudinal movement thereof. 105

Referring more particularly to the drawing, in which the same reference characters are used to designate corresponding parts in 110 the several views, the tool assembly therein shown is of annular form, comprising a pair

of metallic, preferably aluminum, semianular members 1 and 2, secured together by a hinge member 3 about which the semianular members are adapted to relatively 5 rotate to open the tool assembly when desired, and as is more fully disclosed hereinafter. Diametrically opposite the hinge member and at the other ends of the semianular members, are provided integral 10 radially extending semicylindrical members 4 and 5 which may be brought together to form a sort of handle or projecting means by which the tool may be manually operated, as will appear more fully hereinafter. Both 15 the members 4 and 5 are provided with aligned apertures, the aperture 6 being tapered to receive the tapered shank of a pin 7 and the aperture 8 being of sufficient size to receive the stem 9 of the pin 7 upon 20 the threaded end of which is mounted a thumb nut 10 adapted to press or operate against the member 4 in order to maintain the members 4 and 5 compressed together.

The semianular members 1 and 2 are of 25 channel form and are provided with a plurality of radially extending apertures in which are disposed radially movable cutter shanks 11, at the inner end of each of which is rigidly mounted a head 12 in which is 30 mounted a cutting element 13 constructed of suitable tough and strong cutting material, such as high grade steel. The head 12 may be connected to the shank 11 by means of a tongue 14 preferably disposed 35 at an angle to the plane of the tool assembly, and the cutting element 13 is preferably maintained in the head 12 by fused material, or in any other suitable manner. The rear end of the shank 11 is provided with a longitudinal slot 15, adapted to receive a flat key 16 of segmental shape disposed in the slot 17 provided in the periphery of the members 1 and 2, said key being adapted to 40 prevent axial rotation or turning of the shank 11, as well as the members supported thereby, but permitting longitudinal movement of the same. The key member 16 is rigidly maintained in place by small upset or jammed portions 18 of the metal of the 45 periphery of the members 1 and 2, these upset portions being formed by the impact of a suitable tool to cause the edges of the metal to project over the outer edge of the key 16.

Each shank 11 is provided with a plurality of transverse ridges 19 and grooves 20 adapted to cooperate or mesh with counterpart grooves and ridges 19' and 20' on a spiral plate 21. This plate is preferably flat 50 and annular in shape and consists of two semianular parts with their ends normally in abutting contact when the tool is in closed condition. When the ends of said semianular portions abut each other, as when the 55 tool is in closed condition, an endless ring or

spiral plate is substantially formed which is adapted to operate upon all of the shanks 11 when such spiral is caused to rotate or turn about the common axis of the tool and ring. The spiral plate may be provided at 60 its periphery with a guide tongue 22, fitting in a groove 22' provided in the peripheral portion of the members 1 and 2. The inner margin of the spiral plate members may rest upon the surface 23 of the channel 65 members 1 and 2, as is clearly shown in Fig. 3. Each of the portions of the spiral plate 21 may be provided with a perforation 24 adapted to receive the lugs of a spanner wrench, whereby the plate may be caused to rotate in the tool assembly, the spiral 19', 20' thereof causing the shanks 11 to move 70 radially inwardly or outwardly, depending upon the direction of rotation of the spiral 75 plate.

The cutters 13 may be provided with a slight bevel, as shown in Fig. 1, which may be also slightly concaved if desired.

In Fig. 2, I have shown a crank shaft bearing 25 of a crank shaft mounted in its 80 position in an engine with the tool partly in place and in open condition, a portion of the tool being inserted within the engine casing in contact with one side of the bearing 25 and the other portion being in position to be raised to closed position to contact with the other side of the bearing prior to the truing-up operation. The connecting rod 26 is normally connected at one end to the wrist pin of the piston referred to above 90 (not shown), but is disconnected at the other end from the bearing 25 and moved to one side in order to give clearance for the tool.

In Fig. 4 is shown, on a smaller scale, the same portion of the engine crank shaft with 95 the tool in operative position on the bearing. The tool is relatively thin and adapted to be rotated about the bearing between the arms 27 and 28 without any part of the 100 tool contacting therewith.

In operation, the oil pan attached to the bottom of an engine casing may be removed, the connecting rod 26 disconnected from the bearing 25 and the crank shaft suitably turned or moved in its main bearings to 110 lower the bearing 25 to its lowest position, if that is found necessary, for the introduction of the tool. The tool is then opened by removing the nut 10 from the pin 7 and the members 1 and 2 with the parts carried thereby, angularly separated about the pivot or hinge member 3 so as to assume the 115 open condition as shown in Fig. 2. To avoid any portion of the spiral ring projecting from the member 1 or 2 and interfering with a proper opening of the tool, the spiral ring is preferably rotated to bring the ends of the semianular portions thereof into coincidence with the respective ends of the semianular members 1 and 2, after which 120

130

the tool may be readily opened as above indicated. The tool may be then raised into the space in the engine casing so as to bring one of the members, such as member 2, in contact with the bearing 25 at the rear thereof, and then the member 1 raised to close the same about the front of the bearing 25, after which the pin 7 may be placed in the apertures 6 and 8 and the thumb nut 10 threaded to the end of the pin 7 to maintain the members 1 and 2 in closed position. The connecting rod 26 being moved to one side in order to make a clearance for the tool when the same is rotated, the operator 15 or the mechanic may then rotate the tool by hand, or by any other suitable means, if desired, and at the same time may also apply a spanner wrench to the spiral ring 21 so as to cause the same to turn, whereby the 20 spiral grooves and ridges thereof, meshing with the ridges and grooves of the shanks 11, will cause the latter to move radially inwardly as the rotation of the tool progresses, the bearing being acted upon by the cutting 25 elements 13.

It will be apparent that as the tool is relatively thin it may be readily positioned between the arms 27 and 28 of the crank shaft respectively adjacent the ends of the bearing 25 so that no part of the tool will interfere with the arms 27 and 28 as the tool is rotated about the bearing.

It will be further observed that the effective cutting portions of the elements 13 are located along diametric lines so that the pair of cutting elements opposed to each other will always maintain the tool in centered position relative to the center of the shaft or bearing 25, irrespective of how much material is being cut. While such pair of elements 13 is cutting material, other of the elements which may or may not be cutting, or merely bearing against the surface of the shaft, will act as guide members. There is

a certain amount of elasticity in the metal parts, particularly the members 1 and 2, whereby the elements not operating as cutters at any time during the rotation of the tool, will, however, be caused to bear on the surface of the bearing and act as guide members until they arrive at points at which they may obtain a purchase upon the metal to be cut and thus perform a cutting operation. In previous devices, it has been necessary to provide separate means from the cutters to guide the cutting tool relative to the surface to be operated upon. These guiding elements usually are flat at their ends, although, in some cases, slightly con- 60 vex, and chips or burrs cut from the material by the cutters, frequently are caught between the surfaces of the bearing and the guiding element and are jammed therebetween, causing either a marring or scar- 65 ring of the surface of the bearing, or a

throwing out of centered relation of the tool assembly and its cutters with respect to the center of the bearing, thereby causing the cutters to operate irregularly and inaccurately. With my invention, the guiding 70 elements are omitted, whereby no chips or burrs may effect the condition referred to and the cutters themselves are depended upon for performing the function of guiding, while at the same time, operating to cut. 75 As, for example, if a pair of elements 13' are operating and cutting material, a pair of elements 13'' succeeding the same in movement will operate as guide elements on the surface cut by the preceding elements 80 13' and thereby maintain the tool assembly properly centered. It will be observed, however, that the cutting elements 13' will also act as guides on the surface they cut while performing a cutting operation, thus 85 aiding the other elements to maintain the tool properly centered.

By the use of my invention in the manner stated ordinarily only about five or six thousandths of an inch of material is removed before the bearing is brought to circular form. The operator rotates the tool so as to first remove the excess material of the oval portion along the greater diameter thereof and just as soon as the cutters have removed the same and the bearing has reached a circular form, the diameter of which is equal to the smaller diameter of the oval, the operator perceives the same by the "feel" of the tool on the bearing and at 100 that instant he knows that further removal of material is unnecessary since the bearing has attained its correct circular form.

After the operation is complete, the thumb nut 10 may be removed and the tool opened 105 and removed from the engine, the shaft rotated to be connected to the connecting rod 26 and the bearing put into operation as before.

While I have herein described and illustrated upon the drawing one embodiment of the invention and a mode of using the same, it is to be understood, however, that said invention is not limited to the particular details described and shown, nor to the 110 particular use disclosed, but that other forms and uses are comprehended by said invention as do not depart from the spirit of the invention and the scope of the appended claims.

Having thus described my invention, what I claim and desire to protect by Letters Patent of the United States, is:

1. In a tool for operating upon bearings, the combination of hinged semiannular members, radially movable members mounted in said semiannular members, cutting elements carried by said radially movable members and disposed in circular order, semi-annular members having spiral operat- 125 130

ing elements mounted upon said hinged semiannular members, and movable therewith about the hinge thereof, said elements engaging said radially movable members whereby upon rotation of said semi-annular members radial movement is imparted simultaneously to all of said radially movable members.

2. In a tool for operating upon bearings, 10 the combination of a diametrically split circular frame, a diametrically split annular member mounted upon said frame and adapted to rotate about the common axis of said frame and said ring, diametrically opposed cutters disposed in circular order about said axis, radially disposed holders for said cutters movably mounted in said frame and adjacent said ring, enmeshed spiral grooves and ridges on said ring and on 15 said holders whereby angular movement of said ring about said axis causes a simultaneously radial movement of all of said holders and cutters, means for hinging the split portions of said frame whereby said portions may be opened for placing the tool 20 about a bearing, and means for securing said portions in closed condition.

3. In a tool for operating upon bearings, 25 the combination of a sectional hinged annular frame adapted to encompass a bearing, cutting elements supported by said frame, and means for adjusting all of the cutting elements simultaneously towards or away from the encompassed bearing.

- 35 4. In a tool for operating upon bearings, the combination of a sectional hinged annular frame adapted to encompass a bearing, a plurality of respectively diametrically opposed cutting elements, radially disposed 40 holders for supporting said cutting elements movably mounted in said frame, and sectional adjusting means movably mounted on said frame, and in engagement with said holders whereby a movement of said means 45 relative to said frame causes a simultaneous radial movement of all of said holders and cutters in unison.

5. In a tool for operating upon a bearing, 50 the combination of opposed abutting semi-annular frame sections, means for hinging said sections whereby said sections may be angularly separated, means on said sections opposite from said hinging means for securing said sections in closed abutting relation, 55 opposed abutting semiannular ring sections carried upon said frame sections and adapted to be angularly separated upon the rela-

tive movement thereof, cutting elements disposed in circular and diametric relation, and holders for supporting said cutting elements 60 movably mounted in said frame sections and movable therewith, said holders and said ring sections having enmeshing spiral grooves and ridges, and said ring sections when abutting forming a continuous circular spiral ring which upon rotation causes a simultaneous radial movement of said 65 holders and cutters in unison.

6. A tool for operating upon crank shaft 70 bearings comprising a relatively flat circular frame formed of hinged semiannular sections adapted to be angularly separated for the placing of said frame about a bearing to be operated upon and adapted to be inserted and rotated between the connecting crank 75 arms at both ends of the bearing without interfering with said arms, cutting elements carried by said frame, and means on said frame in engagement with said cutting elements for simultaneously radially adjusting 80 all of said cutting elements relative to said bearing.

7. In a tool for operating upon bearings, 85 the combination of semiannular frame sections, hinge members projecting therefrom and pivotally connected together whereby said frame sections may be angularly separated or brought into closed or abutting relation, locking projections on said frame sections opposite from said hinge members, a 90 locking pin for securing said projections together, cutting elements in diametrically opposed and circular relations, holders for said cutting elements comprising cylindrical shanks longitudinally movable in radial 95 bores provided in said frame sections, said shanks being slotted at an end thereof, means passing through said slotted ends and fixed to said frame section for preventing said shanks from rotating about their respective 100 axes, and semiannular ring sections on said frame sections adapted to abut each other to form a continuous circular ring when said frame sections are in closed or abutted relation and adapted to be separated when said frame sections are angularly separated, said ring sections and said shanks provided with enmeshed spiral grooves and ridges whereby movement of said ring sections causes a radial movement of said shanks and cutting 110 elements in unison.

In witness whereof, I have hereunto set my hand this 17th day of May, 1920.

KARL R. PETERS.
